THROTTLE CONTROLLING ATTACHMENT
FOR MOTOR CARS

Harry M. Walker, New Orleans, La.

Application December 12, 1935, Serial No. 54,146

2 Claims. (Cl. 74—482)

This invention relates to throttle valve controlling means for automobiles and the general object of the invention is to provide means whereby in city streets and under other like conditions the engine of an automobile may idle as usual when the foot is taken off of the accelerator pedal but whereby, when the car is traveling in hilly country, the throttle valve may be entirely closed when the foot is removed from the accelerator pedal, the adjusting means for this purpose being located on the dash or instrument board of the car in convenient relation to the driver so that he may at any time adjust the device to suit these two different conditions.

15 A further object is to provide means on the dash or control board of the car adapted to be set in one position to permit idling of the engine and in the other position to permit the throttle valve to be fully closed when the foot is taken off the accelerator pedal.

20 My invention is illustrated in the accompanying drawing wherein:

Figure 1 is a side elevation of my mechanism shown in connection with a carburetor, the dash-board and instrument board being shown in section;

Figure 2 is a detailed elevation of the cam in its position to permit the engine to idle, the foot board being shown in section;

30 Figure 3 is a section on the line 3—3 of Figure 1.

Referring to the drawing, it will be seen that I have illustrated diagrammatically an intake pipe P leading as usual to the manifold of the engine from the carburetor and having therein the throttle valve T of any usual or suitable construction. The throttle valve is ordinarily connected to an operating rod 10 which in turn is connected to the accelerator pedal 11 and to an accelerator controlling lever mounted upon the wheel of the car but not illustrated. Any suitable or usual connections may be made from the accelerator pedal to the valve actuating rod 10, but I have illustrated for this purpose two bell 40 crank levers 12 and 13 operatively connected to each other and to the rod 10 at one end and to the accelerator pedal 11 at the other end. So far, none of the parts which I have described form a part of my invention.

50 It is desirable to provide means whereby when a car is about to travel through hilly country, the throttle valve may be set so that when the foot is taken off the accelerator, the throttle valve may entirely close under the action of the usual 55 throttle valve spring, which means is under the

instantaneous control of the driver and which may be set to permit the partial closing of the throttle valve to permit the engine to idle. I have provided for this purpose a cam 14 pivoted at 15 upon any suitable supporting bracket attached to the dash 5 board of the car. This cam has the arm or extension 16 which is connected to a button 17 or equivalent device shown as being connected by a Bowden wire 18 to the arm 16. Any suitable connection may be made from this button or 10 other actuating device 17 to the arm 16 which will enable this cam to be set in either one or two positions.

Attached to the actuating rod 10 is an arm 19 which at its lower end is formed with the outwardly projecting lugs 20. Passing through these lugs is a rod or pin 21 which is screw threaded for engagement by the nuts 22 so that the rod may be adjusted through the lugs 20 nearer to or further from the cam 14. This pin 21 at its extremity is adapted to abut against the edge face of the cam 14. The arm 19 is clamped upon the rod 10 by any suitable means as, for instance, by the clamping plate 23 held in place by the clamp screws 24. The cam 14 is so formed as shown in Figure 1 that when it is turned to the full line position shown in Figure 2, the radius between the pivot point 15 and that portion of the cam impinged by the pin 21 is sufficiently long as to act as a stop and prevent the rod 10 from moving 30 toward the dash under the influence of the usual spring which commonly controls this rod, beyond the point where the valve T is in idling position. In other words, if the cam 14 be set to the dotted line position in Figure 1, then when the foot is 35 taken off the accelerator pedal 11, the rod 10 will move rearward under the influence of its spring and will almost, but not entirely, close the throttle valve T, and the throttle valve will be in a position for idling. This position of the cam 40 is the one used under normal and ordinary conditions as, for instance, in city streets, but when the cam is set to the position shown in full lines in Figure 1, a lower portion or portion of shorter radius will come opposite the pin 21, and if now 45 the foot be taken off the accelerator pedal, the rod 10 will move rearward under the influence of the spring to a position where the throttle valve may entirely close, thus entirely cutting off the supply of fuel to the engine. The position of the cam 14 is, of course, entirely under the control of the operator, the controlling element being disposed upon the instrument board of the machine or in any other equally convenient place. 50 I have illustrated for the purpose of support 55

ing this cam, the two lugs 25 projecting from a plate 26 attached to the dash, these lugs carrying the vertical bracket 27 to the lower end of which the cam 14 is pivoted. I do not wish 5 to be limited to this, however, nor to the specific details of the construction except as defined in the appended claims.

This device acts as a great saver of gas where 10 a machine is travelling in hilly country as by its means, the operator of the vehicle can at any time as, for instance, at the top of a long hill, shift the cam 14 to the full line position so that when he removes his foot from the accelerator, the 15 throttle valve will entirely close, thus cutting off all flow of the gas to the engine. Of course, the cam 14 does not interfere with the action of the throttle when the accelerator pedal is depressed to give the machine all the gas necessary for going up hill. It only acts as a stop which in one 20 position permits the throttle valve controlling rod to move to entirely close the throttle valve or in another position prevents the throttle valve from entirely closing but limits it in its movement to an idling position.

25 I am, of course, aware that a stop screw is provided on the ordinary carburetor, which may be adjusted to permit the throttle valve to nearly close but prevent it from fully closing when the accelerator pedal is depressed and that it is possible by adjusting this screw, to permit the throttle to fully close, but it is obvious that a driver would have to open the hood of his car and adjust this screw to suit the conditions if he was going 30 to travel over hilly country and then again 35 adjust this screw when he arrived on level country or where his engine would be likely to idle as in the city.

I do not wish to be limited to the details of construction illustrated except insofar as they are 40 embodied in the appended claims.

What is claimed is:—

1. The combination with a throttle valve, a valve operating element, a spring urging the element in a direction to close the valve and an accelerator pedal operatively connected to the element and when depressed opening the valve; of an oscillatably mounted cam having an edge face extending from a point relatively close to the pivotal center of the cam to a point radially further from said pivotal center and there being provided with a stop lug, a member mounted upon the operating element and adapted to be operatively engaged by the edge face of said cam, and manually operable means for oscillating the cam from one position to the other; said cam when shifted in one direction forcing the operating rod in a direction to slightly open the throttle valve and retain the throttle valve open against the action of the spring and when oscillated in the other direction gradually permitting the closing of the throttle valve under the action of the spring. 15 20

2. The combination with a throttle valve, a valve operating element, a spring urging the element in a direction to close the valve, and an accelerator pedal operatively connected to the element and when depressed opening said valve; of a clamp adjustably mounted upon the operating element, a pin carried by said clamp and extending parallel to the operating element, said pin being longitudinally adjustable in the clamp, a cam pivotally supported in the path of movement of the pin, the cam having an eccentric face engaged by the end of said pin and having a stop shoulder at one end of said eccentric face, and manually operable means independent of the accelerator for shifting said cam in one direction to shift the operating rod in a direction to gradually open the valve and in the other direction gradually permitting the valve to close under the action of the spring. 25 30 35
